PRODUCT FOR PRINTING TEXTILE YARNS
AND FABRICS

Moses L. Crossley, Plainfield, Roy H. Kienle and
Chester A. Amick, Bound Brook, N. J., as
signors, by mesne assignments, to American
Cyanamid Company, New York, N. Y., a cor-
poration of Maine

No Drawing. Application August 11, 1938,
Serial No. 224,258

12 Claims. (Cl. 8—70)

This invention relates to a composition for printing textile fabrics and yarns.

In ordinary printing processes, the printer buys separately the dyestuff, reducing agent, thickening agent, assistants and the like, and prepares his own printing paste therefrom. This involves a number of operations by the printer and the printing pastes prepared do not keep very well so that they are usually made up only in sufficient 10 quantities for the immediate printing required.

The object of the present invention is to produce a dry product containing all of the ingredients, that is to say, color, reducing agent, alkali, gum, assistants and the like, which product can 15 be in the form of a powder, flakes, pellets or grains and requires only the addition of water or aqueous media to prepare a printing paste.

It has been proposed in the past to mix a vat dye with Monopole soap and caustic alkali and 20 then to dry the product and blend it dry with hydrosulfite. The product thus obtained was used for vat dyeing. If, instead, it is attempted to obtain a product for vat printing, although British 25 gum as well as vat dye, Monopole soap and caustic alkali are initially mixed together and subsequently dry blended with a reducing agent, e. g., sulfoxylate, the product will not form a satisfactory paste and very inferior prints result.

According to the present invention, all of the 30 ingredients are mixed wet and the product then dried and suitably comminuted. When the drying is effected carefully so as not to overheat, the dry product may be formed into a printing paste by the simple addition of water or suitable 35 aqueous media and excellent prints are obtained being equal and in some cases slightly superior to prints made in the ordinary way; that is to say, where all of the ingredients are formed into a paste without passing through a stage of dry 40 product.

We do not wish to limit the present invention to any particular theory but we believe that the wet mixing and subsequent drying of all the ingredients effects not only a more thorough admixture but probably produces a chemical reaction 45 between certain of the constituents, notably the alkali and gum, altering their characteristics and producing a product which on the addition of aqueous media readily rehydrates and forms a smooth printing paste giving excellent results. The above theory is advanced only as a probable explanation and it is possible that other factors are involved. Therefore, the invention is not limited to any theory.

55 The products of the present invention may be

considered as including certain essential components to which other components may be added if desired. The essential components are the color itself, alkali, (usually alkali carbonates), reducing agent (normally sulfoxylate) and gum. 5 Printing assistants, wetting agents and the like may also be present and are included in more specific aspects of the present invention. It is an important advantage that any of the well known printing assistants may be incorporated in 10 the product of the present invention without in any way reducing the effectiveness of the product and such physically modifying agents as glycerine and the like may also be included.

The present invention is not limited to any 15 particular vat color or, in fact, to a vat color, since it is clearly applicable to the printing with stabilized diazo compounds admixed with coupling components. The gums used are the typical gums employed in printing such as British 20 gum, dextrin, tragacanth, starch and the like, and it is an advantage of the present invention that the ordinary printing practices in this respect are in no sense changed.

The admixture of the wet ingredients may be 25 effected in any suitable manner which will produce a complete homogeneous mixture. Very satisfactory results are obtained by mixing as a rather thick paste, for example in a dough mixer, and although the invention is in no sense limited 30 to this particular method of admixture, in a more specific aspect this preferred modification is included.

The drying of the homogeneously admixed 35 components is very important. In general, this should be effected at a temperature below that at which the hydratable constituents such as the gum are affected to the extent that they do not readily rehydrate. Preferably, drying is carried out in vacuo in order to permit greater speed but the important thing is to maintain the temperature at a point below that at which the material 40 is damaged and any drying method which permits maintaining a low temperature may be employed. Although not limited to a particular temperature, 45 we prefer to use temperatures not exceeding 60° to 65° C.

The invention will be described in conjunction 50 with the following specific examples which illustrate typical combinations of various colors with different proportions of paste forming ingredients. The invention is not limited to the details set forth in the specific examples which are intended to be typical illustrations only. More particularly, the procedure of drying, aging, etc.,

given in the examples is not intended to limit the invention as any of the other standard methods of drying, aging and the like may be used. The parts are by weight.

5

Example 1

A printing thickener is prepared by heating 2000 parts of British Gum No. 177 (Stein Hall) and 6000 parts of cold water in a double boiler 10 with continuous stirring at a temperature from 85° to 88° C. for 90 to 120 minutes. The source of heat is removed, the stirring continued, and 450 parts of potassium carbonate and 450 parts of sodium carbonate immediately added. When 15 the thickener has cooled to approximately 66° C., 900 parts of sodium formaldehyde sulfoxylate are thoroughly incorporated. Subsequently, sufficient water is added to bring the total to 10,000 parts.

20 25 parts of a dispersible Vat Navy Blue powder (chlorinated dibenzanthrone) containing 32% real dyestuff and prepared according to United States Patent No. 2,090,511 are added to 975 parts of the above thickener and after thorough 25 stirring, dried under 29 inches of vacuum in an aluminum pan at 60° to 65° C. for approximately 72 hours. After being dried, the product is crushed to yield coarse flakes.

These flakes are re-hydrated to give a printing 30 color paste containing 36.6% solids which is essentially the same amount of real dye as is present in the printing color paste before drying. The re-hydrated paste is slightly thicker than printing color pastes prepared in the usual manner 35 from similar ingredients. It is reduced with water to the same apparent consistency as tested by hand-stirring, struck off on bleached and mercerized 80 square cotton cloth, dried in an oven at 60° to 80° C., aged for five minutes in a 40 steam box at 104° C., soaped at the boil with 0.5% soap solution, and then ironed dry. The resultant print is redder and stronger than that obtained from an ordinary printing paste of equivalent dye strength prepared from the same percentages 45 of ingredients.

Example 2

25 parts of Vat Yellow GC powder (Color Index 1118) prepared according to United States Patent 50 No. 2,090,511 are added to 975 parts of the thickening agent prepared as in Example 1 and the procedure of Example 1 followed, except the paste was dried in a copper tray.

63.4 parts of cold water are added to 36.6 parts 55 of the solid material obtained as above described, forming a smooth printing paste which is further diluted with 5 parts of water to yield a product with satisfactory printing consistency. This color is printed, aged, oxidized, and finished as in Example 1 and the resulting print is redder and 60 stronger than that obtained from an ordinary printing paste prepared from the same components.

Example 3

65 Using the procedure of Example 2, 25 parts of Vat Pink (6,6'-dichloro-4,4'-dimethyl-2,2'-bithionaphthenindigo) powder, prepared according to United States Patent No. 2,090,511, are added to 975 parts of printing thickener as described in 70 Example 1, and the mixture dried in a copper tray. The dried product is then coarsely ground to yield small pellets.

63.4 parts of water are added to 36.6 parts of 75 these pellets yielding a paste. Prints made therefrom on cotton are yellower and appreciably

stronger than those obtained from a portion of the same printing color paste which had not been dried, ground and rehydrated.

Example 4

5

25 parts of Orange R powder, Color Index 1217, prepared according to United States Patent No. 2,090,511 and containing about 6 parts real dye, are added to 975 parts of the printing thickener prepared as in Example 1, intimately mixed and 10 handled as in Example 2.

63.4 parts of cold water are added to 36.6 parts of this dried material and the mixture stirred until the paste is uniform. It is then printed on bleached, unmercerized 80 square cotton cloth, 15 and finished in the usual manner. The resulting prints are yellower and their color value is equal to the prints obtained from the original undried printing color paste, which had not been dried, ground and rehydrated. 20

Example 5

25

A printing thickener is prepared by thoroughly mixing 2100 parts of B-2 British gum, 200 parts of tapioca flour, 500 parts of cornstarch and 2500 parts of cold water and heating in a double boiler with constant stirring until 1300 parts of water have evaporated, about 90 to 120 minutes. Stirring is continued until the paste has cooled.

400 parts of the above thickener are charged 30 into a laboratory dough mixer, 100 parts of powdered potassium carbonate added thereto, and the mixture worked until uniform. 160 parts of sulfoxylate, 60 parts of glycerine and 100 parts of Scarlet 2 GHN powder or a mixture of Hydron 35 Pink and Hydron Orange, containing about 36 parts of real dye, are added in the order given, each being intimately mixed before the addition of the next ingredient. The product is dried under 29 inches of vacuum in an aluminum pan at 40 60° to 65° C. This product puffs readily in the vacuum oven which is an asset in obtaining an easier rehydratable powder. The dried product is ground to give a fine powder, which, when rehydrated and printed, gives a smooth scarlet 45 print of good color value.

Example 6

50

The procedure of Example 5 is followed exactly except that an additional 1 part of anthraquinone (3.3 parts of a 30% anthraquinone paste) was added as a printing assistant. This product is dried in a Monel metal tray, then ground to a fine powder. When rehydrated and printed, smooth bright scarlet prints are obtained, but 55 with improved color yield over that obtained in Example 5.

Example 7

60

The procedure of Example 5 is followed exactly except that an additional one part of alpha anthraquinonyl-monamide of maleic acid is added as a printing assistant. The product is dried in an aluminum tray in vacuo and ground to a fine powder.

Example 7 gives a better color yield than Example 5 when rehydrated and printed on cotton. 65

Example 8

70

A sample of wet presscake of the dyestuff used in Example 2 is dispersed with the sodium salt of disulfodinaphthylmethane and adjusted with water to contain 15% real color. 10 parts of this slurry is mixed with 90 parts of printing thickener prepared as in Example 1 except that 6% glycerine by weight is added prior to making up

to 10,000 parts. The resulting paste is then dried azeotropically, using mineral spirits and operating under 28" to 29" vacuum.

The dried product obtained is rehydrated with 5 water, homogenized in a buhrstone mill, and printed on pigmented rayon. At 10 minutes aging, smooth, bright, pink prints are obtained.

Example 9

10 The procedure of Example 5 is followed except that 100 parts of the Vat Pink powder described in Example 3 is used as the dyestuff and the product is dried in vacuo at 60° to 65° C. When printed on pigmented rayon, a strong, bright, 15 pink print is obtained.

Example 10

10 The procedure of Example 9 is followed with the addition of 1% ferric chloride on the weight of the final powder, during the formulation. Prints from this material after rehydration give color yields much stronger than those obtained in Example 9.

Example 11

25 The procedure of Example 9 is followed except for the substitution of 1% aluminum sulfate for the ferric chloride. Prints after rehydration are superior to those obtained in Example 9.

Example 12

30 The procedure of Example 9 is followed with the substitution of beta methyl umbelliferon for the ferric chloride. Prints obtained from this product are superior to those obtained from the 35 product prepared in Example 9.

Example 13

40 The procedure of Example 9 is followed with the addition of 60 parts of the butyl ether of ethyleneglycol with the glycerine. Prints obtained from this product are superior to those obtained from the obtained from the product prepared in Example 9.

Example 14

45 The procedure of Example 13 is followed, substituting diethylene glycol for the butyl ether of ethyleneglycol. Prints obtained from this product are superior to those obtained from the product prepared in Example 9.

Example 15

50 2100 parts of B-2 British gum, 500 parts of cornstarch and 200 parts of tapioca flour are slurried with 1080 parts of Vat Pink presscake (Example 3), containing 300 parts real dye, dispersed with the sodium salt of disulfodinaphthylmethane, and 2200 parts of cold water. The mixture is cooked with stirring until the total weight is 4300. The heat is then removed, 1000 parts of 55 solid potassium carbonate being added and the stirring continued until the solution is completed. When this mixture has cooled to approximately 65° C., 1600 parts of sulfoxylate are added and the stirring continued until dissolved, after which 60 65 600 parts of glycerine are added and the stirring is continued until the material is cooled down. This mix is dried at 60° to 65° C. in vacuo. The prints obtained from the rehydrated product are bright and strong.

Example 16

70 A dispersed powder is prepared by treating 56 parts of an equimolar mixture of 2-methyl-5-chlorobenzene-diazo-biguanide and the ortho-toluidine of 2-hydroxy-3-carboxy naphthalene with

3 parts of the sodium salt of disulfodinaphthylmethane, 70 parts water, 40 parts dextrine and 2 parts trisodium phosphate according to the method described in United States Patent No. 2,090,511. 20 parts of this powder are mixed with 56 parts of water, 24 parts of 5 N sodium hydroxide solution, 20 parts of Cellosolve and 80 parts of a neutralized starch-tragacanth paste, prepared by slurring 150 parts wheat starch in 850 parts water, adding 150 parts gum tragacanth (make up 6 oz. per gallon) then cooking in a double boiler, at 180° to 190° F. for 2 hours with stirring. After intimate mixing is accomplished, the material is vacuum dried for 12 hours at approximately 100° F. then further dried for 6 hours at 160° F. When the product is rehydrated, printed on a cellulose fabric and acid aged, it gives a print of excellent strength and brightness.

What we claim is:

1. A dispersible solid product capable of dispersion in aqueous media to give a finished printing paste comprising in combination a color, an alkali, and print thickening ingredients, the said components having been admixed in wet form 25 and dried at a temperature below that at which the dehydration becomes irreversible.

2. A dispersible solid product capable of dispersion in aqueous media to give a finished printing paste comprising in combination a vat dye, 30 an alkali, a reducing agent capable of transforming the vat dye into the leuco compound, and the printing thickening ingredients, the said components having been admixed in wet form and dried at a temperature below that at which the dehydration becomes irreversible.

3. A dispersible solid product capable of dispersion in aqueous media to give a finished printing paste comprising in combination a diazo compound stabilized against coupling in alkaline solution, a coupling component, an alkali and the printing thickening ingredients, the said components having been admixed in wet form and dried at a temperature below that at which the dehydration becomes irreversible.

4. A dispersible solid product capable of dispersion in aqueous media to give a finished printing paste comprising in combination a vat dye, an alkali, a reducing agent capable of transforming the vat dye into the leuco compound, printing thickening ingredients and a printing assistant, the said components having been admixed in wet form and dried at a temperature below that at which the dehydration becomes irreversible.

5. A dispersible solid product capable of dispersion in aqueous media to give a finished printing paste comprising in combination a vat dye, an alkali, a reducing agent capable of transforming the vat dye into the leuco compound, printing thickening ingredients and a hygroscopicity modifying agent, the said components having been admixed in wet form and dried at a temperature below that at which the dehydration becomes irreversible.

6. A method of producing a solid product capable of forming a printing paste on mixture with an aqueous medium which comprises mixing in aqueous dispersion a color, an alkali, and a printing thickening agent, until homogeneous admixture results and drying the product at a temperature below that at which the dehydration becomes irreversible.

7. A method of producing a solid product capable of forming a printing paste on mixture with

- an aqueous medium which comprises mixing in aqueous dispersion a vat dye, an alkali, a reducing agent capable of transforming the vat dye into the leuco compound and printing thickening ingredients until homogeneous admixture results and drying the product at a temperature below that at which the dehydration becomes irreversible.
8. A method of producing a solid product capable of forming a printing paste on mixture with an aqueous medium which comprises mixing in aqueous dispersion a diazo compound stabilized against coupling in alkaline solution, a coupling component, an alkali, and printing thickening ingredients until homogeneous admixture results and drying the product at a temperature below that at which the dehydration becomes irreversible.
9. A method of producing a solid product capable of forming a printing paste on mixture with an aqueous medium which comprises mixing in aqueous dispersion, a vat dye, an alkali, a reducing agent capable of transforming the vat dye into the leuco compound, printing thickening in-

gredients, and a printing assistant, until homogeneous admixture results and drying the product at a temperature below that at which the dehydration becomes irreversible.

10. A method of producing a solid product capable of forming a printing paste on mixture with an aqueous medium which comprises mixing in aqueous dispersion, a vat dye, an alkali, a reducing agent capable of transforming the vat dye into the leuco compound, printing thickening ingredients and a hygroscopicity modifying agent until homogeneous admixture results and drying the product at a temperature below that at which the dehydration becomes irreversible. 15

11. A process according to claim 7 in which all of the components are mixed in the form of a stiff aqueous paste.

12. A process according to claim 8 in which all of the components are mixed in the form of a 20 stiff aqueous paste.
